UNITED STATES PATENT OFFICE.

SAMUEL BARUCH, OF NEW YORK, N. Y.

SEAL AND KNOT PROTECTOR.

Application filed April 5, 1924. Serial No. 704,319.

To all whom it may concern:

Be it known that I, SAMUEL BARUCH, a citizen of the United States, and resident of the city of New York, borough of Manhattan, in the county of New York and State of New York, have invented certain new and useful Improvements in Seal and Knot Protectors, of which the following is a specification.

10 The present invention relates to improvements in seal and knot protectors of the general character disclosed in my Patent No. 1,074,769 of October 7, 1913, in which two telescoping inter-locking members provide a 15 chamber or cavity adapted to receive and protect the knotted or united ends of a cord or wire. The patented device also included a guard member adapted to prevent the insertion of an instrument for effecting dis- 20 engagement of the two locking members.

In the device of said patent the bead which connects the two sections of one member is on the outside where a skilled mechanic provided with the proper type of tools might 25 after considerable very careful effort succeed in raising the bead, reducing the diameter thereof and separating the parts without mutilating the same sufficiently to attract the attention of an ordinary user. Thereafter 30 he might reassemble the parts.

It is an object of the present invention to overcome this possible objection by so designing the parts that the bead is within the knot chamber where access cannot be gained 35 thereto and I thereby effectively prevent the unauthorized disassembly and reassembly of the device.

With my improved device the guard section constitutes a wall of the knot receiving 40 chamber and entirely encloses and conceals one of the interlocking sections and their seam or joint is on the inside instead of on the outside of the knot chamber.

In the accompanying drawings Fig. 1 is 45 a central longitudinal section through a device constructed in accordance with my invention and showing in section a portion of a package wall.

Fig. 2 is a central longitudinal section 50 through one of the locking members.

Fig. 3 is a similar view through the locking section of the other member; and

Fig. 4 is a similar view through the guard section prior to the assembly of the guard 55 section and the locking section with which it is permanently associated.

My improved knot protector comprises two inter-engaging or interlocking members 10 and 11, the member 11 being formed of two sections, 12 and 13, permanently connected together. The section 12 interlocks with the member 10 and the section 13 constitutes a guard which effectively prevents the insertion of a tool to effect disengagement of the section 12 with the interlocking member 10. All three of the sections are formed of stamped, spun or otherwise fashioned sheet metal, the character and gauge of which is dependent upon the use for which the completed device is designed.

The member 10 is substantially cup shaped, including an end wall 14 and a peripheral wall 15. At the open end of the cup the peripheral wall 15 is provided with an inwardly and backwardly turned flange 16 adapted for interengagement with a flange formed on the section 12 of the member 11. The section 12 is substantially ring shaped and of appreciably less diameter than the cup shaped member 10. A flange 17 is turned outwardly and backwardly from one edge of the ring shaped member 11 and is preferably concavely curved, lying substantially flat against the outside of the ring adjacent to its point of union with the ring and flaring outwardly therefrom at its free edge. One of these flanges preferably the flange 17 is sub-divided into a series of spring fingers. The member 11 at its other edge is formed with an inwardly turned annular flange or lip 18 adapted to be engaged by the guard 13.

The guard section 13 of the member 11 is substantially cup shaped and relatively shallow. It includes an end wall 19 and a narrow peripheral wall 20 adapted to encircle and embrace the free edge of the peripheral wall 15 of the member 10, when the members 10 and 11 are assembled. The end wall 19 has a central circular depression 21 of approximately the same diameter as the aperture in the end of the section 12. To effect a permanent connection of the guard 13 and the section 12, the depressed portion 21 of the guard section is spun, swaged or stamped to flatten it and form a bead and a groove 22. The latter receives the flange and the forming of the bead firmly clamps the flange between the two walls of the groove.

The central portion of one of the sections, as for instance the portion 21 of the guard,

is formed with one or more openings 25 through which may be passed the ends of a cord or wire 26 wrapped about a package 27, or passed through any part to be sealed as for instance a meter. The ends are then twisted or knotted together. The sections 10 and 11 are then united by telescoping them and forcing the flange 16 downwardly past the fingers 17 until the fingers spring 10 back into place beyond the flange. The important feature of my improved construction is the forming of the bead on the inside instead of the outside of the knot chamber so that the prying up of the bead is 15 impossible. The two members may be relatively rotated but such rotation is without effect in so far as their continued inter-engagement is concerned. Pressure exerted directly upon the central section 21 of the 20 guard section will not result in restoring this member to the shape shown in Fig. 4. It will merely result in rupturing the guard section. The only way in which the guard section and locking section of the member 11 25 can be separated without permanently mutilating them is to exert pressure on the bead of the guard section which co-operates with the main body thereof to form the groove 22. When the two interlocking members are 30 assembled, however, access cannot be had to the interior of the knot receiving chamber for this purpose.

It will be obvious that certain changes 35 and alterations might be made in the general form and arrangement of the parts described without departing from the spirit of the invention, or the scope of the appended claims.

What I claim as new and desire to secure 40 by Letters Patent is:

1. A seal and knot protector comprising a pair of inter-engaging members forming a knot receiving chamber, one of said members including a locking section and a guard 45 section permanently connected together, said guard section constituting a wall of the knot receiving chamber, said locking section being of general ring shape and including an internal flange permanently connected to the guard section.

2. A seal and knot protector comprising a pair of inter-engaging members co-operating to form a knot receiving chamber, one of said members including a ring shaped locking section and a guard section, said locking section having an internal flange permanently secured to said guard section.

3. A seal and knot protector comprising a pair of inter-engaging members telescoping 60 to form a knot receiving chamber, one of

said members including a ring shaped locking section and a guard section, said locking section having an internal flange and said guard section being formed with an outwardly opening annular groove receiving 65 said flange.

4. A knot protector comprising a pair of interlocking members telescoping to form a knot receiving chamber, one of said members including an annular locking section 70 and a guard section including an offset central portion extending inwardly and permanently secured to the annular locking section.

5. A seal and knot protector comprising 75 two telescoping members, inter-engaging locking devices carried by the members, and means concealing the inter-engaging locking devices comprising a guard section permanently attached to the interior of one of the 80 telescoping members.

6. A seal and knot protector comprising two telescoping members, inter-engaging locking devices carried by the members, and means concealing the inter-engaging locking devices comprising a guard section permanently attached to the interior of one of the 85 telescoping members, said guard section co-operating with the other telescoping member to form a knot receiving chamber. 90

7. A seal and knot protector, comprising two telescoping members cooperating to form a knot receiving chamber, one of said members having an end wall, and a peripheral wall presenting at its open end an inwardly and backwardly extending flange, and the other of said members including two sections, one comprising a peripheral wall adapted to telescoping inside of the first mentioned member and presenting an annular series of outwardly and backwardly extending fingers at one end adapted to snap past said flange to effect interlocking of the members when they are telescoped, said section also presenting an internal flange at the 105 other end, and the other of said sections including a peripheral wall adapted to telescope outside of the first mentioned member, and an end wall having a central circular depressed portion disposed within the last 110 mentioned end of the other section and extending radially outward to form a bead and permanently retain the two sections together with the last mentioned flange held between said bead and the end wall which 115 carried the bead.

Signed at New York city in the county of New York and State of New York this 4th day of April A. D. 1924.

SAMUEL BARUCH.
